UNITED STATES PATENT OFFICE.

GEORGE HENRY CULVERWELL AND GEORGE STEPHEN COX, OF OAK PARK, ILLINOIS.

CLOSURE FOR BARRELS.

1,359,874.

Specification of Letters Patent. Patented Nov. 23, 1920.

Application filed February 21, 1919. Serial No. 278,498.

To all whom it may concern:

Be it known that we, GEORGE HENRY CULVERWELL and GEORGE STEPHEN Cox, citizens of the United States, residing at Oak Park, 5 in the county of Cook and State of Illinois, have invented a new and useful Closure for Barrels, of which the following is a specification.

Our invention relates to a closure for 10 barrels and the object of our invention is to provide a simple means for securely locking the cover in the opening of the barrel, thereby insuring a non-leakable closure.

It is a further object of our invention, 15 to provide a useful opening in metal barrels, for the paint manufacturer for mixing directly in the barrel, also for filling the barrel with ready mixed paints and other liquids. It is also an important object of 20 our invention to provide a closure for barrels, by means of which they can be easily emptied and cleaned.

With the above and other objects in view, 25 our invention consists in the improved combination and the arrangements of the several elements, to be hereinafter described and then more particularly pointed out in the appended claims.

We attain these objects by the mechanism 30 illustrated in the accompanying drawings.

Figure 1 is a plan view of the end of the barrel.

Fig. 2 is a vertical sectional view of the barrel on line 9—9 of Fig. 1.

Fig. 3 is a detail view of the cam lock.

Fig. 4 is a plan view of the end of the barrel, showing a modified form of our invention.

Fig. 5 is a vertical sectional view of the 40 barrel on line 9^a—9^a of Fig. 4.

Fig. 6 is a detail view of the ratchet tooth cam lock.

Fig. 7 is a detail view of the wrench.

Referring in detail to the drawings, and 45 particularly to Fig. 1 and Fig. 2 thereof, 1 indicates a circular opening in the end of the barrel, provided with a downwardly extending conical flange. Seated in opening 1 is cover 2 formed with a convex upper 50 surface, a circular strengthening groove, and an upwardly extending conical flange of a corresponding angle and size to make a forced fit in combination with the gasket 3 in the barrel's opening 1. Mounted centrally on top of cover 2 is an upwardly extending shoulder stud 5, on which the actu-

ating cross bar 4 is fulcrumed and retained. The actuating cross bar 4 is of rectangular shape, provided with a hole midway of its length extending through its flatwise portion, and of convenient size to fulcrum on stud 5.

The locking elements of the closure shown in Fig. 1 on line 9—9, are the tapered edge cam locks 7—7^a disposed diametrically opposite each other on the end of the barrel, at a convenient distance from the edge of opening 1, to allow the insertion of cover 2. In Fig. 3 we show the tapered edge cam locks 7—7^a more clearly in detail, having 70 an outwardly extending flange for fastening it to the end of the barrel, an upwardly extending angular formed portion on one end of proportionate height to allow the entrance of the actuating cross bar 4 under the cam edge. The edge then tapering downward proportionately along its circular length, from which the necessary energy is imposed on the actuating cross bar 4, to seat cover 2 in opening 1. The cam locks 80 7—7^a are also provided with a series of threaded holes and a lock screw 8.

To operate this closure, cover 2 with the gasket 3 is inserted into opening 1 with the actuating cross bar 4 in a cleared position 85 of the cam locks 7—7^a, then manually turning the cross bar 4 the ends of which are brought under and in contact with the edges of the cam locks 7—7^a and by a continual turning of the cross bar 4, a downward pressure is created on cover 2 forcing cover 2 into a wedged seat in opening 1. The cross bar 4 is then locked in its advanced position by the lock screw 8.

In the modified construction shown in 95 Figs. 4, 5 and 6 and 7, the tapered edge cam locks 7^b—7^d are provided with inverted ratchet teeth, spaced proportionately along the camming edge and are clearly shown in detail in Fig. 6. The cam locks 7^b—7^d are 100 provided with slotted lugs on one end, which, in connection with the wrench 10, are used to operate the closure. When manual pressure on the cross bar 4 is discontinued said cross bar 4 has a tendency to 105 recede from under the edges of the cam locks 7^b—7^d. Further movement of cross bar 4 is prevented by coming in contact with the vertical edges of the ratchet teeth on the cam locks. In this construction the 110 cam locks 7^b—7^d are not located diametrically opposite each other, one being slightly

- in advance of the center line, so as to facilitate the releasing of the cross bar 4. The wrench 10, shown in detail in Fig. 7, is provided with a pilot hole of convenient size 5 to fulcrum on the end of stud 5, said hole in wrench 10, is located midway of its length extending through the flatwise portion. It is also provided with a raised lug and a stud 10^a extending through on each 10 side, and a slot on one end, which is used to operate the closure. In other respects, the construction of the closure illustrated in Figs. 4 and 7 is similar to that previously described.
- 15 To operate the closure, cover 2 with the gasket 3 is inserted in opening 1 with the cross bar 4 in a cleared position of the cam locks 7^b—7^d. With the aid of wrench 10 piloted on the end of stud 5, and stud 10^a 20 in contact against the edge of cross bar 4 as indicated by 11, by manually turning wrench 10, the ends of cross bar 4 are brought under and in contact with the ratchet teeth of the cam locks 7^b—7^d and are 25 prevented from releasing by the vertical edge of the ratchet teeth. To release the closure as shown in Fig. 4, the slotted end of wrench 10 is inserted in the slotted lug of the cam lock 7^b, the raised lug resting on 30 top of, and stud 10^a against the edge of the cross bar 4 and by a manual pressure downward and to the left on the other end of wrench 10, the end of the cross bar 4 is 35 disengaged from the ratchet tooth. By alternately applying the same operation to each end of the cross bar 4, the cover 2 can be easily removed.
- 40 From the foregoing description taken in connection with the accompanying drawings, the construction, manner of operation and the several advantages of the invention will be clearly understood. This closure is particularly designed for use on metallic barrels, for the convenient handling of 45 paint and other liquids, and to provide an opening for cleansing the barrel, though of course not necessarily limited to such use. It is obvious that our closure may be used for a great variety of purposes. For example, it is capable of effective use on metallic barrels, tanks, drums, receptacles and 50 containers. It may in fact be used with any kind of a cover, closure or stopper, where a locked closure is needed.
- 55 It is highly essential in the application of a closure to metallic barrels, to provide

60 a positive locking means and a leak proof closure, to prevent a possible leakage caused by the rough usage and handling in shipping.

65 It is of course manifest that this closure may be made in various sizes and also other forms, in accordance with the form and capacity of the particular barrel to which it is to be applied. It is also understood that there may be ways of using one or more of the clamping means to lock this closure. It is further to be understood, that while we have herein shown and particularly described several constructions of a practical 70 character, it is manifest that the construction and relative arrangement of the several elements employed, may be considerably varied in many respects, without departing from the spirit or abandoning any of the 75 advantages of the invention as claimed.

76 We claim—

77 1. The combination with a barrel having a circular opening and a downwardly extending conical flange, of a closure therefor 80 including a cover member formed with a convex upper surface, a circular strengthening groove and an upwardly extending conical flange to fit the barrel's opening, an actuating cross bar, a plurality of radially 85 disposed clamping elements, for engaging the actuating cross bar when manually operated under said clamping elements, that simultaneously urges the cover member to its applied position in the barrel's opening, 90 a lock screw in the clamping elements for locking the actuating means.

95 2. The combination with a barrel having a circular opening and a downwardly extending conical flange, of a closure therefor 100 including a cover member, an actuating means, a plurality of radially disposed clamping elements on the end of the barrel, each clamping element having an outwardly extending flange for fastening it to the end of the barrel, an upwardly extending angular formed portion on one end of proportionate height to allow the entrance of the actuating bar, a downwardly extending camming edge tapering downward from the open end proportionately along its circular length, a series of threaded holes in the raised portion and a lock screw for locking the actuating means.
